Adjustable bandage for an infant, which is particularly suitable when it is desired to support the infant's waist and to hold the infant's hips in a proper position, the bandage being simple in construction, being easy to apply to the infant, being comfortable to wear, and being readily removable for washing whenever necessary.

UNITED STATES PATENT OFFICE

2,618,260

ADJUSTABLE BANDAGE FOR A HERNIA OF THE GROIN

Winifred A. Blegen, York, N. Dak.

Application August 3, 1951, Serial No. 240,187

3 Claims. (Cl. 128—95)

1

This invention relates to improvements in hernia appliances, and more particularly to a hernia-supporting bandage for an infant.

A main object of the invention is to provide a novel and improved hernia bandage particularly suitable for use with an infant, said bandage being simple in construction, being easy to apply to the infant, being comfortable to wear, and being readily removable for washing whenever necessary.

A further object of the invention is to provide an improved hernia bandage for an infant, said bandage being inexpensive to manufacture, being usable over and over again, being reversible for use on either side of the infant, and being adjustable in size, so that it may be employed for a relatively long period of time.

Further objects and advantages of the invention will become apparent from the following description and claims, and from the accompanying drawings, wherein:

Figure 1 is a pictorial view of an infant wearing an improved hernia support constructed in accordance with the present invention, the support being shown in front view;

Figure 2 is a pictorial view of the infant of Figure 1 in back view;

Figure 3 is an enlarged perspective view showing the improved hernia support device illustrated in Figures 1 and 2, the support device being shown in completely tied position;

Figure 4 is a perspective view of the improved support device shown in untied condition preparatory to placement thereof on an infant.

Referring to the drawings, and more particularly to Figure 4, the improved support device comprises a pair of elongated sections 11 and 12, each section comprising a plurality of strands of soft material, such as wool yarn, the ends of the sections being bound or tied, as shown at 13, to prevent the strands of yarn from becoming separated. The elongated sections 11 and 12 are placed in side-by-side relationship and are tied, preferably with a square knot, as designated at 15, at an off-center intermediate portion thereof to define a doubled loop 16. When thus tied, a pair of relatively long ends 17 and 18 are defined, and also defined are a pair of relatively short ends 19 and 20.

In using the device, the knot 15 is fitted over the rupture to hold it in place and the two longer ends 17 and 18 are passed around the hips of the infant, one of said ends being passed through the loop 16, and the ends are tied together by a knot 21. The two shorter ends 19 and 20 are then

passed around the infant's waist and tied around the rear portion of the waist-encircling ends 17 and 18, as by a knot 22, shown in Figure 3. By thus tying the shorter ends 19 and 20 together around the rear portion of the waist-encircling section ends 17 and 18, the knot 15 is held firmly in place and kept from slipping. As shown, bow knots are preferably employed at 21 and 22 to enable the device to be readily unfastened for removal and washing whenever required.

It will be readily apparent that the bandage described above may be employed on either side of the infant's body, and is readily adjustable in size in accordance with the growth of the infant. The sections 11 and 12 preferably comprise soft woolen yarn material to prevent chafing or irritation of the infant's skin and to allow the device to conform to the contours of the infant's body.

The knot 15 is of relatively large size, since it is formed by knotting the double sections 17 and 18, whereby the knot has a substantial area and provides a firm and distributed support for the hernia.

While a specific embodiment of an improved hernia device has been disclosed in the foregoing description, it will be understood that various modifications within the spirit of the invention may occur to those skilled in the art. Therefore, it is intended that no limitations be placed on the invention except as defined by the scope of the appended claims.

What is claimed is:

1. A hernia appliance for infants comprising a support consisting of a pair of elongated sections, each comprising a plurality of strands of soft material, said sections being disposed adjacent each other and knotted at an off-center intermediate portion thereof to define a doubled loop, one pair of ends being relatively long and the other pair of ends being relatively short, the long ends being adapted to be passed around an infant's waist and tied together through said loop, with the knot supportingly positioned adjacent the infant's groin, and the shorter ends being adapted to be passed beneath the infant's groin and to be tied together around the portions of the sections at the back of the infant.
2. A hernia appliance for infants comprising a support consisting of a pair of elongated sections, each section comprising a plurality of strands of soft yarn-like material disposed adjacent each other and formed with a square knot at an off-center intermediate portion thereof to define a

doubled loop adjacent the knot, one pair of ends defined by said knot being relatively long and the other pair of ends being relatively short, the long ends being adapted to be passed around an infant's waist and tied together through said loop, with the knot supportingly positioned adjacent the infant's groin, and the shorter ends being adapted to be passed beneath the infant's groin and to be tied together around the portions of the sections at the back of the infant.

3. A hernia appliance for infants comprising a support consisting of pair of elongated sections, each section comprising a plurality of strands of soft woolen yarn material, said sections being disposed adjacent each other and knotted at an 15.

off-center intermediate portion thereof to define a doubled loop, one pair of ends being relatively long and the other pair of ends being relatively short, the long ends being adapted to be passed around an infant's waist, one of said long ends being adapted to be passed through said loop and to be tied to the other of said long ends, with the knot supportingly positioned adjacent the infant's groin, and the shorter ends being adapted to be passed beneath the infant's groin and to be tied together around the portions of the sections at the back of the infant.
